Patented Apr. 20, 1920.

Inventor,
Astrod Hermelin,
BY Geo. F. Maitly
ATTORNEY

UNITED STATES PATENT OFFICE.

ASTRID HERMELIN, OF NEW YORK, N. Y., ASSIGNOR TO GREELY SQUARE HOTEL COMPANY, A CORPORATION OF NEW YORK.

DESIGN FOR A DOLL.

54,918.

Specification for Design.

Patented Apr. 20, 1920.

Application filed October 20, 1919. Serial No. 332,119. Term of patent 7 years.

To all whom it may concern:

Be it known that I, ASTRID HERMELIN, a subject of the King of Sweden, residing in the borough of Manhattan, city, county, and State of New York, have invented a new, original, and ornamental Design for a Doll, of which the following is a specification, reference being had to the accompanying drawing, forming part thereof.

The figure is a front view of a doll, showing my new design.

I claim:

The ornamental design for a doll, as shown.

ASTRID HERMELIN.

Witnesses:

ARTHUR L. LEE,
W. C. BREHM.
